CUTTING AND FOLDING MECHANISM FOR
PRINTING MACHINESAdolph M. Zuckerman, New York, N. Y., assignor
to R. Hoe & Co., Inc., New York, N. Y., a cor-
poration of New York

Application December 1, 1937, Serial No. 177,488

5 Claims. (Cl. 270—6)

The invention relates to web cutting mechanisms for printing machines and particularly to an improvement in such mechanisms whereby the same will more efficiently and desirably cut sheets from webs coming from printing machines.

It is often desirable to cut the products from a newspaper or magazine printing machine by a clean cutting knife instead of by the usual serrated knife. It is therefore proposed to provide in a web cutting mechanism for this type of printing machine a combination, of a newspaper or magazine folder having the usual serrated knife and collecting pins and which may be operated at relatively high speed, and a pair of clean cutting cylinders, better adapted to be operated at a somewhat lower speed, whereby one cutting mechanism may be conveniently used in the clean cutting of products when desired, or the other may be used at higher speed in the cutting of products wherein a serrated cut is not objectionable. The arrangement may be used to advantage with other than the combination of a folding cylinder and a former, it being also applicable for use with a collecting cylinder and web turning bars.

One of the objects of this invention is to provide, in a web cutting mechanism for a printing machine, a combination of cutting devices whereby the web coming from the machine may be selectively cut into sheets by either cooperating cylinders having clean cutting knives, or a serrated knife.

A further object is to provide in a web cutting mechanism the combination of a pair of clean cutting cylinders with a folder having a serrated knife, and arranged to permit either cutting means to be operated while the other is inoperative.

It is also an object of the invention to provide a web cutting mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

The preferred embodiment of the invention is illustrated in the accompanying drawings, wherein:

Figure 1 is a side elevation of a web folding,

cutting and collecting mechanism embodying the features of this invention;

Figure 2 is an enlarged end view of a pair of clean cutting cylinders partially sectioned to show the cooperating knives;

Figure 3 is a diagrammatic plan view showing the action of a clean cutting knife upon the web;

Figure 4 is an enlarged end view of cooperating, collecting, folding and cutting cylinders with a pair of folding off rollers partially in section to show the operation thereof;

Figure 5 is a diagrammatic plan view of the cutting cylinder showing the action of a serrated knife upon the web; and

Figure 6 is a diagrammatic end view of an arrangement embodying the features of this invention as applied to a combination of collecting and transfer cylinders and web turning bars.

The features and principles of this invention are shown in Figure 1 as being applied to a web folding mechanism having a driven web guide roller 11 from which the web 12 is directed over a former 13 and between cooperating rollers 14 and 15 whereby it is folded longitudinally, and then between a pair of driven nipping rollers 16 and 17. From the nipping rollers 16 and 17, the folded web 12^a is guided by suitable guides 18 between a pair of cooperating driven clean cutting cylinders 19 and 21, which may be set to cut the web into sheets as will be hereinafter described. The sheets if cut, or if not cut, the folded web 12^a, is guided by suitable guides 22 between another pair of driven nipping rollers 23 and 24 and guides 25, to cooperating cylinders 26 and 27, being respectively a folding cylinder 26 and a cutting cylinder 27. The folding cylinder 26, as will be explained more in detail hereinafter, cooperates with a pair of folding off rollers 28 and 29 to fold the sheets, as cut by either the cylinders 19 and 21, or the cylinders 26 and 27, and deliver them to a rotating fly 31 from which they are removed and deposited upon a delivery belt 32. From the belt 32, the products may be transferred to another belt 34.

Herein the several driven rollers and cylinders are indicated as being driven from a common driving shaft 35 which, it will be understood, is drivingly connected to the drive of the printing machine and driven in synchronism therewith, and has a bevel gear 36 secured thereon in mesh with a gear 37 secured on a vertically disposed shaft 38. The roller 11 has its shaft 39 drivingly connected to the shaft 38 by means of meshed bevel gears 41 and 42 respectively secured on each shaft. The nipping rollers 16 and 17 are,

as usual, geared together for opposite rotation and are driven by a gear 43 secured to a shaft 44 which is drivingly connected to the shaft 38 by means of meshed gears 45 and 46 respectively secured on each shaft.

5 The clean cutting cylinders 19 and 21 are geared together by gears 47 and 48 respectively secured to the shafts 49 and 51 respectively of each cylinder. A bevel gear 52 secured on the shaft 10 49 of cylinder 19 is in mesh with a gear 53 secured on a shaft 54, which is drivingly connected to the shaft 38 by means of meshed gears 55 and 56 respectively secured on each shaft. The nipping rollers 23 and 24 are, as usual, geared together 15 for opposite rotation and are driven by a gear 57 secured to a shaft 58 which is drivingly connected to the shaft 38 by means of meshed gears 59 and 61 respectively secured on each shaft.

20 The folding cylinder 26 and the cutting cylinder 27 are geared together by gears 62 and 63 secured to the shafts 64 and 65 respectively of each cylinder. A bevel gear 66 secured on the shaft 64 of the cylinder 26 is in mesh with a gear 67 secured on a shaft 68 which is drivingly connected to the shaft 38 by means of meshed gears 69 and 71 respectively secured on each shaft. A train of meshed pinion gears 71, 72, 73, 74 and 75, of which gear 71 is in mesh with a gear 76 25 on the cylinder shaft 64, forms the means to drive the folding off rollers 28 and 29 in opposite directions of rotation. The fly 31 is driven through a gear 77 secured on the fly shaft 78 in mesh with a gear 79 secured on a shaft 81, which is 30 drivingly connected to the shaft 38 by meshed gears 82 and 83, secured respectively on each shaft.

Referring to Figures 1, 2 and 3, the clean cutting cylinders 19 and 21 are mounted between 40 opposing machine frames 89 with their respective shafts journaled in brackets 91 and 92 respectively which may be bolted, or otherwise secured, to the respective frames 89. The web cutting means on the cylinders 19 and 21 are herein 45 shown as comprising knife blades 93 and 94, which are respectively and releasably secured to each cylinder in holders 95 and 96 respectively, by means of bolts 97 and 98. The knife blades 93 and 94 extend lengthwise of the respective cylinder and are set at an angle to the axis thereof, in accordance with the usual practice, see Figure 50 3. The cylinders are each also set at an angle in respect to the web 12a, whereby when the cooperating blades 93 and 94 meet they will provide a shearing action upon the web to produce a clean straight cut transversely across the web, the edge at the cut being substantially at right angles to the edge of the web. Cooperating clean cutting cylinders constructed and mounted as 55 60 shown and described in Patent No. 1,558,140 are adapted for use as cylinders 19 and 21.

Referring to Figures 1, 4 and 5, the cylinders 26 and 27 and the folding off rollers 28 and 29 are mounted between the frames 89 with the respective shafts thereof journaled in suitable bearings therein. Herein the shaft 64 of the cylinder 26 is journaled in brackets 99 and the shaft of the cylinder 27 is journaled in brackets 101, which brackets are suitably secured to the frames 89. 65 70 The cylinder 26 is provided with protractable pins 102, see Figure 4, and the usually provided tucking blades 103, the blades 103 being suitably actuated to tuck sheets cut from the web into the bite of the folding off rollers 28 and 29 at timed 75 intervals. The construction and operation of

the pins 102 and the blades 103 with the folding off rollers 28 and 29 is well understood, and need not be further described in detail, reference being made to patent to Halliwell, No. 1,499,106, dated June 24, 1924 for a complete and detailed description of the same. The cylinder 27 is provided with a web cutting blade 104 which is releasably held in a block 105 and at each revolution of the cylinder cooperates with rubber or like members 106 provided in the cylinder 26 to sever the web 12 into sheets. The blades 104 are generally serrated at their cutting edges and disposed in the cylinder 27 in alignment with the axis thereof, see Figure 5.

The arrangement shown in Figure 6 illustrates 1 the embodiment of the features and principles of this invention in a combination including a collecting cylinder and an arrangement of web turning bars and wherein a former such as 13 is not required. In this embodiment, the web is 2 slit and fed over turning bars 111, each web strip 112, 113 and 114 being fed into juxtaposed relation between a pair of cooperating nipping rollers 115 and 116 from which they pass between a pair of cooperating clean cutting cylinders 117 and 118 constructed and formed as above described in respect to the cylinders 19 and 21. The cut sheets or web strips depending on whether the cylinders 117 and 118 are in operation or not, are then fed between nipping rollers 119 and 120 3 from which the same is fed between cutting cylinders 122 and 123. Cooperating with the cutting cylinder 123 is a collecting cylinder 124, having the usually provided tucking blade and pins, whereby in the well known manner, the 4 products after they are advanced by the cylinder 123, are folded as they are transferred to a folding cylinder 125, from which they are delivered to delivery cylinders 126 and 127. From the cylinders 126 and 127, the products are delivered to 5 suitable delivery belts 128 and 129 respectively.

Due to the above combinations and arrangements of the features and principles of this invention, it is possible to either cut the web into sheets by the clean cutting cylinders 19, 21 or 4 117, 118, or by the serrated blade 104 on the cylinder 27 or on cylinder 122 as desired. The change-over from one to the other may be easily accomplished without inconvenience nor substantial loss of time, it being necessary only to 5 either separate the cylinders 19 and 21 by any suitable means, or to remove the knives 93 and 94 on these cylinders to cause them to become inoperative to cut the web, whereby it will be fed between the same to the cylinders 26 and 27 to 5 be cut by the blade 104. The removal of the blade 104 from the cylinder 27 permits the web to be cut by the knives 93 and 94 on the clean cutting cylinders 19 and 21 and be collected by the cylinder 26 and folded thereby in cooperation 6 with the folding off rollers 28 and 29.

It will be understood that the invention may be embodied in other specific forms without departing from the spirit or essential attributes thereof, and it is therefore desired that the present embodiment be considered in all respects as 6 illustrative and not restrictive, and it will be further understood that each and every novel feature and combination present in or possessed by the mechanism herein disclosed forms a part 7 of the invention included in this application.

What I claim is:

1. In a web cutting and folding mechanism for a printing machine, the combination of means to feed the web through said mechanism, a pair 7

of cooperating clean cutting cylinders adapted to receive the web therebetween and sever it into sheets, a pair of cooperating serrated blade web cutting cylinders adapted to receive the web therebetween and to sever it into sheets, said cooperating pairs of cylinders being arranged to receive the web in sequence and to selectively act thereon, one cylinder of one of said pairs of cylinders having sheet folding means thereon to fold the sheets cut from the web by the selected pair of sheet cutting cylinders, and common means to drive said cylinders in synchronism.

2. In a web cutting and folding mechanism for a printing machine, the combination of two pairs of cooperating web cutting cylinders spaced apart sufficiently to insure that a sheet cut from the web by one pair will be free from the other pair, one of said pairs of cylinders having clean cutting knives thereon and the other pair of cylinders having serrated blade web cutting means thereon, said pairs of cylinders being arranged to receive the web in sequence and to selectively act thereon, one cylinder of one of said pairs of cylinders having sheet folding means thereon to fold the sheets cut from the web by the selected pair of sheet cutting cylinders, and common means to drive all of said cylinders in synchronism.

3. In a web cutting and folding mechanism for a printing machine, the combination of, spaced apart supporting members, means mounted between said members to feed a web through said mechanism, a delivery device mounted between said supporting members to receive products from said mechanism, a pair of clean cutting cylinders mounted between said members and cooperating to cut the web into sheets, a pair of cooperating serrated blade web cutting cylinders mounted between said members, spaced from said clean cutting cylinders, and disposed below the same, said last mentioned pair of cylinders including a sheet collecting and folding cylinder adapted to collect and fold the product from either pair of cutting cylinders, means cooperating with said sheet collecting and folding cylinder to receive the sheets and to deliver them to said delivery device, a common drive shaft adjacent said members, and means connecting each of said web

feeding means, said delivery device, said pair of clean cutting cylinders, said serrated blade web cutting cylinders and said sheet receiving and delivering means with said common shaft to drive them all in synchronism, whereby said mechanism is adapted to selectively collect and fold sheets cut from the web by said clean cutting cylinders or to collect and fold sheets cut from the web by said serrated blade web cutting cylinders.

4. In a web cutting and folding mechanism, the combination of a pair of cooperating clean cutting cylinders adapted to receive the web therebetween and sever it into sheets, a pair of serrated blade web cutting cylinders to receive the web and sever it into sheets, and being spaced from said clean cutting cylinders an amount sufficiently to insure that sheets cut from the web by said clean cutting cylinders will be free therefrom before they are received by said serrated blade web cutting cylinders, said pairs of cylinders being adapted to selectively operate on the web, one of the cylinders of said pair of serrated blade web cutting cylinders having means thereon to collect and fold sheets cut from the web by either of said pairs of cylinders, and common driving means for said pairs of cylinders to drive them in synchronism, whereby the cylinder having the sheet collecting and folding means thereon will be operated at the proper speed to collect and fold sheets cut from the web by the selected pair of cylinders.

5. In a folder for a printing machine, means to feed a plurality of webs to a cutting and folding mechanism the cutting device of which is provided with a serrated edge cutting member that may be rendered ineffective when it is desired to fold previously cut products, a delivery device to which the products are forwarded from the folding mechanism, and coacting rotary cutting members in the path of the web being led to the folding mechanism, said rotary cutting members being driven in synchronism with the folding mechanism and operable to cut the webs into sheets at times when the serrated edge cutting member is ineffective.

ADOLPH M. ZUCKERMAN.
